UNITED STATES PATENT OFFICE.

ROBERT M. DIXON, OF EAST ORANGE, NEW JERSEY, ASSIGNOR TO THE SAFETY CAR HEATING & LIGHTING COMPANY, A CORPORATION OF NEW JERSEY.

GAS-LAMP.

956,572.

Specification of Letters Patent.

Patented May 3, 1910.

Application filed June 22, 1906. Serial No. 322,821.

To all whom it may concern:

Be it known that I, ROBERT M. DIXON, residing at East Orange, in the county of Essex and State of New Jersey, have invented certain new and useful Improvements in Gas-Lamps, of which the following is a full, clear, and exact description, such as will enable others skilled in the art to which it appertains to make and use the same.

10 This invention relates to gas lighting apparatus, and appertains more particularly to improvements in lamps adapted for lighting railway cars or similar structures.

One of the objects of the invention is to 15 provide a construction adapted to facilitate the ventilation of the structure to be lighted.

Another object contemplated is to so arrange the parts constituting the lamp structure that the draft created by the outgoing 20 air from the car or similar structure will not prevent a steady and uninterrupted flow of air into the mixing chamber of the lamp.

Another object is to provide an improved 25 method of suspending a lamp from the ceiling of the structure to be lighted.

Other objects will be in part obvious and in part pointed out hereinafter.

The invention accordingly consists in the 30 features of construction, combinations of elements and arrangement of parts which will be exemplified in the embodiment hereinafter set forth, and the scope of the application of which will be indicated in the following claims.

35 In the accompanying drawing, wherein is illustrated one of the various possible embodiments of my invention,—the figure is a view in section taken through a portion of a railway car, showing a lamp constructed in accordance therewith suspended from the ceiling.

In order to render certain objects of my invention more clearly understood it may be pointed out that in railway service it is especially desirable to furnish a firm and steady support for the lamps, which are usually suspended from the ceilings of the cars. Inasmuch as the openings or chimneys which extend through the roofs of the cars and

50 carry off the products of combustion from the lamps are utilized as means of ventila-

tion for the interior of the cars, it is desirable that the parts of the lamps be arranged in such manner that the outgoing vitiated air will not interfere with or prevent a steady 55 flow of air to the mixing chambers thereof.

From the following detailed description of the relative arrangement of the features comprising my invention it will be apparent that I have obtained the above and other 60 desirable ends through the provision of an exceedingly simple and efficient structure.

Referring now to the drawing, 1 denotes a portion of the roof and 2 a portion of the ceiling of a railway car formed with an 65 opening 3 suitably lined as at 4, and over this opening and fastened to the roof of the car is a chimney 5. Chimney 5 has riveted thereto as at 6, a flaring ring 7, and is provided with a dome-shaped cap 8, a space being formed between the ring and the cap to allow the products of combustion flowing up through the chimney to pass into the atmosphere. In order to prevent cinders and other foreign substances from entering the chimney 75 the same is provided with an encircling hood 9 supported in position opposite the opening between ring 7 and cap 8 by means of radially extending members 10 secured at their inner portions between ring 7 and 80 cap 8, said members also acting as spacing blocks for said parts. I also preferably provide a screen as at 11 as an additional means for preventing foreign substances from entering the interior of the car and lamp 85 through the chimney.

Arranged beneath opening 3 is a ceiling plate 12 having a plurality of apertures 13, said ceiling plate being also provided with a plurality of raised portions or bosses 14 90 upon its upper edge, so that when the same is secured to the ceiling of the car as by means of screws 15 passing through the bosses, air passageways 16 will be provided between said plate and the ceiling, through 95 which air within the car may pass into the chimney. In the present instance I have interposed a ring 17 between ceiling plate 12 and the ceiling of the car.

Extending inwardly and upwardly from 100 ceiling plate 12 and integral therewith are a plurality of arms 18 joined at their inner

ends, said arms constituting an integral spider 19. The point of jointure of said arms is bored as at 20 to provide a passageway for the entering gas. Extending downwardly through cap 8 and threaded into a suitable fitting 21 resting thereon is a gasway 22, the lower end of which has a threaded connection with the upper end of aperture 20 of spider 19. Threaded into the opposite end of aperture 20 of spider 19 is a member 23 carrying an adjustable gas-regulating device 24 and an adjustable inspirator nozzle 25. Member 23 is held in any adjusted position in spider 19 by means of a lock-nut 26 threaded exteriorly thereof and adapted to engage a wall of said spider.

The body of the lamp is constituted by a casting 27 the upper end of which is internally screw-threaded to engage with threads upon the depending end of member 23, said member acting as an immediate means of support of the lamp body from spider 19. Lamp body 27 is provided with a plurality of openings 28 extending upwardly therethrough to accommodate the products of combustion of the lamp and deliver the same into the interior of ceiling plate 12, whence they pass upward and out through the chimney, and has also a plurality of laterally extending air ports 29 which lead from the exterior of the lamp into the mixing chamber 30 adjacent the end of inspirator nozzle 25. Threaded in ports 29 are nipples 31, the outer ends of which are adjacent the lower end of ceiling plate 12. The object of this arrangement of the means for admitting air into the mixing chamber is to prevent the flow of air from the interior of the structure through the apertures of ceiling plate 12 from interfering with the steady flow of air into the mixing chamber of the lamp whereby an even mixture of gas and air is secured, thus insuring a steady combustion at the burner and a constant amount of illumination.

Depending from body portion 27 and having a threaded connection therewith is a burner nozzle 32, and exteriorly of the lower portion of said burner nozzle is, in the present instance, threaded a dished perforated member 33 carrying a depending deflector-ring 34. Spun into member 33 is a supporting ring 35 for the globe 36, said globe, as shown, having a flared upper portion to which is suitably secured a ring 37. Ring 37 has a threaded connection with supporting ring 35, a strip of relatively soft material 38 being wrapped about the edge of the globe and additional cushioning means being interposed between said strip and a ring 39 which has a threaded connection with ring 37.

Resting upon shoulders 40 formed on body portion 27 is a deflector-ring 41, the lower

portion of which extends about supporting ring 35 and provides an air passageway 42 therebetween, said parts being spaced by suitable bosses 43 formed upon body portion 27. Supporting ring 35 is perforated as at 44 to allow air passing up through passageway 42 to enter the interior of globe 36, which in the present instance I have shown open at the bottom. Threaded upon member 33 is a spool 45, to which is tied or otherwise secured a pendent mantle 46.

The operation of my invention should be apparent without further description, but it will be noted that ventilation of the structure to be lighted is secured by the provision of an air passageway between the ring and the ceiling, and that the apertured ceiling plate also provides an efficient means of ventilation. The integral spider of the ceiling ring from which the lamp body depends, furnishes an exceedingly stable support therefor.

A further advantage presents itself in that as the air inlet ports are removed from the influence of the outgoing currents of air a steady flow of air for the burning mixture is at all times secured, thus insuring an even flame within the mantle.

As many changes could be made in the above construction and many apparently widely different embodiments of my invention could be made without departing from the scope thereof, I intend that all matter contained in the above description or shown in the accompanying drawings shall be interpreted as illustrative and not in a limiting sense.

Having thus described my invention, what I claim as new and desire to secure by Letters Patent is:—

1. A gas lighting apparatus comprising, in combination, a hollow upright cylinder passing through the ceiling of the railway car or similar structure to be illuminated, and forming a chimney, an annular member depending from the ceiling and having a plurality of converging arms, a lamp body, connections between the lamp body and central portions of said arms adapted to support said lamp body from said arms, and a gasway descending centrally through said chimney and attached to said arms.

2. A gas lighting apparatus comprising, in combination, an annular member having a peripheral perforate portion in the shape of an inverted, truncated cone, a plurality of arms converging inwardly from the periphery of said member, and means supporting a lamp body from said arms.

3. A gas lighting apparatus comprising, in combination, an upright hollow cylinder extending through a ceiling and forming a chimney, an annular member arranged at

- the lower end of said cylinder and having a plurality of upwardly converging arms joined together within said cylinder, a lamp body below said member, and connections 5 extending from said lamp body to the joined ends of said arms.
4. An apparatus of the class described comprising, in combination, a hollow cylinder passing through a ceiling and forming 10 a chimney, a ventilator overlying said cylinder, an annular member underlying said cylinder, and a tension member passing centrally down said chimney and secured at one end to said ventilator and at the other 15 end to said member.
5. In gas lighting apparatus of the class described, in combination, a lamp body, a member depending from the ceiling of the structure to be lighted and having a plurality 20 of arms extending inwardly from the periphery of said member to form a coupling, and means for suspending said lamp body from said coupling.
6. In gas lighting apparatus of the class 25 described, in combination, a lamp body, a chimney, a member depending from the ceiling of the structure to be lighted and providing an air space between the same and the ceiling, a plurality of converging 30 arms extending upwardly and inwardly from the periphery of said member to form a spider from which the lamp body is suspended, and a gasway leading down within 35 said chimney to said spider.
7. In gas lighting apparatus of the class 40 described, in combination, a member adapted to be secured to the ceiling of a railway car or similar structure, said member having a plurality of arms extending inwardly and joined at their inner ends to an upwardly 45 extending hub, said hub having an opening extending upwardly therethrough, a gasway threaded into the upper open end of said hub, a lamp body, and means threaded into the lower open end of said hub and extending to said lamp body.
8. In gas lighting apparatus of the class 50 described, in combination, a member adapted to be secured to the ceiling of a railway car or similar structure and having a plurality 55 of arms extending inwardly and joined at their inner ends, the jointure of said arms having an opening extending therethrough, a gas-way leading into one 60 end of said opening, a member carrying an inspirator nozzle extending into the opposite end of said opening, and a lamp body threaded upon said member, said lamp body being provided with a plurality of laterally-extending air inlet passageways which lead into the mixing chamber thereof.
9. In gas lighting apparatus of the class 65 described, in combination, an apertured member adapted to be secured to the ceiling of the car or similar structure and having 70 interiorly thereof an integral spider, said spider having an opening extending through its central portion, a gas-way extending downwardly through the roof of the car and threaded into said opening, means carrying 75 an inspirator nozzle threaded into the opposite end of said opening, a lamp body threaded upon said last-mentioned means, and air inlet passageways leading into the mixing chamber of said lamp body from a 80 position below said apertured member.
10. In gas lighting apparatus for railway cars or similar structures, in combination, an apertured ceiling-plate depending from the ceiling of the car, said plate having a 85 plurality of arms extending from its inner surface to form an integral spider, said spider having an opening extending through the same, a gas-way extending through the ceiling of the car and threaded into the 90 opening in said spider, a member carrying an inspirator nozzle threaded into the opposite end of said opening, and a lamp body having a threaded connection with said member and being provided with laterally-extending air inlet passageways.
11. In gas lighting apparatus for railway cars or similar structures, in combination, a ceiling plate having a plurality of apertures and being provided interiorly with an integral apertured spider, a gas-way extending 95 downwardly through the roof of the car and having a threaded connection with the aperture in said spider, a member carrying an inspirator nozzle threaded into the aperture of said spider with which said gas-way communicates, and a lamp body having a mixing chamber and threaded upon said member and having laterally-extending air inlet ports which lead from a position below 100 105 said ceiling plate into the mixing chamber of said lamp body.
12. In gas lighting apparatus for railway cars or similar structures, in combination, a ceiling having a suitable opening there- 110 through, ventilating means co-acting therewith comprising an apertured plate secured to said ceiling beneath said opening, said plate being provided interiorly with an integral spider centrally apertured to form 115 a passageway for the entering gas, a gas-way extending downwardly through the opening in said ceiling and having a threaded connection with the aperture in said spider, a member carrying an inspirator 120 nozzle having a threaded connection with the aperture in said spider and with which said gas-way communicates, a lamp body having a mixing chamber and threaded upon said member, and air inlet ports ex- 125 tending laterally through said lamp body

and into the mixing chamber thereof, said air inlet ports being located below said apertured plate.

13. In gas lighting apparatus for railway cars or similar structures, in combination, a ceiling having a suitable opening therethrough, ventilating means co-acting therewith comprising an apertured plate secured to the ceiling immediately beneath the opening therein, said plate having arranged interiorly thereof an integral apertured spider constituted by a plurality of inwardly and upwardly extending arms joined at their inner ends, a gas-way extending downwardly through the roof of the car and threaded into the aperture of said spider, a member carrying an inspirator nozzle threaded into the aperture of said spider, means carried by said member for holding the same against turning, a lamp body threaded upon said member exteriorly thereof and having a plurality of laterally-extending air inlet ports, and nipples threaded into said air inlet ports and leading upwardly therefrom beneath said apertured plate.

14. In gas lighting apparatus for railway cars or similar structures, in combination, a ceiling having a suitable opening therethrough, ventilating means co-acting therewith comprising an apertured plate secured to said ceiling beneath said opening, said plate being provided interiorly with an integral spider apertured to provide a passageway for the entering gas, a gas-way extending through the opening in the ceiling of said car and having a threaded connection with said spider, a member carrying an inspirator nozzle threaded into said spider with which said gas-way communicates, a lamp body threaded upon said member, said lamp body having a plurality of laterally-extending air inlet ports, nipples threaded into said air inlet ports and leading outwardly therefrom to a position adjacent the lower end of said apertured plate, a burner nozzle threaded into said lamp body, and apertured means threaded upon said burner nozzle, a globe carried by said last-mentioned means, and an annular member supported by said lamp body which surrounds said globe supporting means and provides an air-passageway therebetween, whereby air may be admitted to said globe.

15. In gas lighting apparatus for railway cars or similar structure, in combination, an apertured ceiling member certain portions of which are spaced from the ceiling of the car by means of bosses whereby air-passageways are formed between the same and the ceiling, said air-passageways leading through an opening in the roof of the car whence they pass to the atmosphere, an in-

tegral spider formed interiorly of said ceiling member by a plurality of arms which extend inwardly and upwardly therefrom and which are joined at their inner ends, the jointure thereof being apertured to provide a passageway for the entering gas, a gas-way leading through the opening in the roof of the car and having a threaded connection with the aperture in said spider, a member carrying an inspirator nozzle threaded into the aperture of said spider, a lamp body threaded upon said member, a burner nozzle depending from said lamp body and having a threaded connection therewith, apertured means threaded upon said burner nozzle through which the products of combustion pass whence they pass through openings in said lamp body to be delivered within said ceiling member, a flanged ring carried by said apertured means, a globe suitably secured to said flanged ring, and a member depending from said lamp body which surrounds said flanged ring and provides an air-passageway therebetween, said flanged ring being perforated to admit air into the interior of the globe which passes through the passageway between said last-mentioned member and said flanged ring.

16. In gas lighting apparatus for railway cars or similar structures, in combination, a ceiling member certain portions of which are spaced from the ceiling of the car by means of bosses whereby air-passageways are formed between the same and the ceiling, means extending through said bosses for securing said ceiling member in position beneath an opening which extends through the roof of the car, a capped chimney arranged above said opening on the exterior of the car, an integral spider formed interiorly of said ceiling member, said spider being apertured in the central portion thereof, a gas-way extending through the cap of said chimney downwardly through the opening in the roof of the car and having a threaded connection with the aperture in said spider, a member carrying an inspirator nozzle threaded into the aperture of said spider, a lamp body having a threaded connection with said member and supported thereby, said lamp body having a plurality of passageways for carrying off the products of combustion from the lamp and having a plurality of air inlet ports extending laterally therethrough into the mixing chamber, said air inlet ports receiving air from a position beneath said ceiling member, a burner nozzle depending from said lamp body and having a threaded connection therewith, a globe, and apertured means carried by said burner nozzle and forming a part of the support of said globe.

17. In gas lighting apparatus of the class

described, in combination, a lamp body, a burner nozzle depending therefrom, an apertured deflector member secured to said burner nozzle, a globe carried by said member, and means surrounding said member and providing an air passage between said means and said member whereby air may be admitted to said globe.

18. In gas lighting apparatus of the class described, in combination, a lamp body, a burner nozzle depending therefrom, an apertured deflector threaded to said burner

nozzle, a globe carried by said member and an annular member supported by said lamp body which surrounds said globe supporting member and forms therewith an air passage whereby air may be admitted to said globe. 15

In testimony whereof I affix my signature, in the presence of two witnesses.

ROBERT M. DIXON.
